UNITED STATES PATENT OFFICE.

JOHN EDWIN FOXLEE, OF CHICAGO, ILLINOIS.

OVEN.

1,253,866.

Specification of Letters Patent.

Patented Jan. 15, 1913.

Application filed June 27, 1912. Serial No. 177,882.

To all whom it may concern:

Be it known that I, JOHN E. FOXLEE, a subject of the King of Great Britain, residing at Chicago, in the county of Cook and State 5 of Illinois, have invented certain new and useful Improvements in Ovens, of which the following is a specification, reference being had to the accompanying drawings.

This invention relates to certain improvements in ovens and has relation more particularly to a device of this general character of a portable type, and it is an object of the invention to provide a novel and improved device of this general character 15 which may be employed with a maximum of efficiency in connection with a gas range or ring, a coal range, or electrical heating apparatus.

It is also an object of the invention to 20 provide a novel and improved device of this general character comprising two coacting sections adapted to rest one upon the other, the lower section being open at both ends with the upper or second section having its 25 top closed together with supporting shelves operatively engaged with the lower section.

The invention has for a further object to 30 provide a novel and improved device of this general character including means co-acting with the upper portion or section of the oven to reduce heat radiation together with controllable vent openings to permit the escape of heat and vapor from within the oven.

The invention consists in the details of 35 construction and in the combination and arrangement of the several parts of my improved oven wherein certain important advantages are attained and the device rendered simpler, less expensive and otherwise more convenient and advantageous for use, as will be hereinafter more fully set forth.

The novel features of my invention will 40 hereinafter be definitely claimed.

In order that my invention may be the better understood I will now proceed to describe the same with reference to the accompanying drawings wherein,

Figure 1 is a view in vertical section taken 45 through an oven constructed in accordance with an embodiment of my invention with the handle of the bottom section shown in fragments; and

Fig. 2 is a fragmentary sectional view 50 illustrating a slightly modified form of construction.

In the accompanying drawings A denotes the bottom section of my improved oven which is herein disclosed as circular in top plan. The opposite ends of the section A 55 are open and the marginal portions of said section A are provided with the outstanding beads 1. Arranged within the section A at substantially its center is a circular shelf 2 having radiating therefrom the arms 4 secured as at 5 in any desired manner to the section A. Extending at right angles from a face of the shelf 2 at predetermined points inwardly of the margin thereof are the headed studs 6 disposed through a second 70 circular disk or shelf 7. The disk or shelf 7 is maintained in a predetermined spaced relation relative to the shelf or disk 2 through the medium of the sleeves 8 surrounding the studs 6 and interposed between said shelves 75 or disks 2 and 7.

B denotes an upper section of my improved oven and the top of said section is closed as indicated at 9. The lower or free marginal portions of the side wall of the section B are disposed outwardly to afford a flange 10 adapted to contact with or rest upon a bead 1 of the section A. If preferred however the lower or open end portion of the upper section may be provided 80 with an outwardly disposed bead 11 as indicated in Fig. 2 which is adapted to rest upon a bead 1 with the portion of the section below said bead 11 telescopically engaged within the lower section.

As herein set forth the upper section B 85 has disposed thereover a shelf or casing 12 extending a predetermined distance beyond the lower or open end of the section A. The shell or casing 12 is also spaced a predetermined distance from the section B and is maintained in such spaced relation through the medium of suitable heat insulating material 14 interposed between the top or closed end of the section B and the top or closed 100 end of the shell or casing 12. Disposed through the top or closed end of the section B and the shell or casing 12 and the interposed material 14 are the vent openings 15 which serve to permit the escape of the 105 heated air or vapors within the oven and said openings 15 are under control of the plate 16 rotatably mounted upon the outer face of the closed end or top of the shell or casing 12 and said plate is provided with the 110 openings 17 adapted to register with the openings 15. Radiating from the plate 16

is an arm 18 terminating in an upstanding finger piece 19. The arm 18 is adapted to contact with a side arm of the outstanding hand grasp or handle 20 carried by the section B or more particularly the shell or casing 12. When the arm 18 is in contact with the hand grasp or handle 20 the opening 17 of the plate 16 will be in registry with the openings 15. When the sections A and B are in assembled relation and the section A is properly positioned relative to a heating medium such as a gas range or ring, a gas stove or an electrical heating apparatus the lower plate or disk 7 serves as a baffle plate for properly deflecting the heat upwardly within the section B. A baking pan P or the like is adapted to be rested upon the upper disk or shelf 2. When it is desired to reduce the heat relative to the pan P positioned within the section A, the section A is inverted so that the shelf or disk 7 is uppermost and which will result in said disk or shelf 7 being positioned up higher in the section A.

At predetermined points therearound the section A is provided with a plurality of series of inwardly directed studs 21. The studs of each series are in predetermined vertical spaced relation and also spaced a predetermined distance apart circumferentially of the section A. 22 denotes a third shelf or disk having depending from the marginal portions thereof the legs 23 having their lower or free end portions bifurcated or forked as indicated at 24 so that said lower or free end portions of the legs 23 may straddle the studs 21 for supporting the third disk or shelf 22 within the section B. The position of the third shelf or disk 22 may be vertically adjusted in accordance with the studs 21 with which the legs 23 may be engaged.

The section A at substantially diametrically opposed points is provided with the outstanding handles 25 whereby the assembled sections A and B may be readily transported or the section A carried independently of the section B.

From the foregoing description, it is thought to be obvious that an oven constructed in accordance with my invention is particularly well adapted for use by reason of the convenience and facility with which it may be assembled and operated and it will also be obvious that my invention is susceptible of some change and modification without materially departing from the appearance and spirit thereof and for this reason I do not wish to be understood as limiting myself to the precise arrangement and formation of the several parts herein shown in carrying out my invention in practice except as hereinafter claimed.

I claim:

A portable oven comprising two separable sections, one of said sections having its opposite ends open, the second section having one end closed, a plurality of inwardly directed studs carried by the first named section, the studs of each series being transversely and circumferentially spaced, a disk, and arms depending from the disk and the lower end portions of the arms being forked for detachable engagement with the studs, said arms being of such a length as to position the disk above the first named section when the arms of the disk are in engagement with the studs.

In testimony whereof I hereunto affix my signature in the presence of two witnesses. 80

JOHN EDWIN FOXLEE.

Witnesses:

H. HAMBERGER,
ISADORE S. KRINSKY.
